UNITED STATES PATENT OFFICE.

VOLNEY R. CHAMBERLIN, OF CAMBRIDGE, MASSACHUSETTS.

WINDOW-SCREEN.

SPECIFICATION forming part of Letters Patent No. 288,921, dated November 20, 1883.

Application filed September 17, 1883. (No model.)

To all whom it may concern:

Be it known that I, VOLNEY R. CHAMBERLIN, of Cambridge, in the county of Middlesex and State of Massachusetts, have invented a new and useful Improvement in Adjustable Window-Screens, which will, in connection with the accompanying drawings, be herein-after fully described, and specifically defined in the appended claims.

This invention relates to that class of adjustable window-screens which are described and shown in the application for Letters Patent of the United States filed by me on the 7th day of April, 1883, and numbered 90,938, of the series of 1880; and the invention consists in the construction and combination of the divers devices embodied therein, as will, in connection with the accompanying drawings, be herein-after more particularly described and claimed.

In said drawings, Figure 1 is a plan view, showing two corners of a screen with my improvement thereto applied. Fig. 2 is a horizontal section taken on line XX, Fig. 1. Fig. 3 is a perspective view of the corner of a screen with my combined fly-guard and lip-supporter thereto applied.

In said views, *a* represents a section of the lower rail. *b* is a section of the upper rail, and *c* the side rail, the middle portion being broken away in order to enlarge the parts shown, the parts *b* *c* being shown in section parallel with the plane of the screen, and as taken on line W W, Fig. 2. An expanding bar, *d*, having a lip, *e*, is secured to the frame of the screen by guide-rods *f* *f*, which are screw-threaded in part of their length, and are screwed into bar *d*, as shown. Said rods are inserted in holes *g* in the frame, and a helical spring, *h*, is mounted upon each rod, and is housed in a chamber, which is an enlargement of hole *g*. The shoulder at the inner end of said chamber serves as the abutment, against which the inner end of said spring bears.

In order that the springs shall exert a uniform pressure upon bars *d*, whether the same are at a greater or less distance from rail *c*, I

mount the correspondingly-threaded nuts *i* on rods *f*, to serve as an abutment against which the outer end of springs *h* act, and by turning said nuts along the rods the requisite distance the required expansive force of the coiled spring may be utilized to hold bar *d* against the window-jamb with the necessary pressure, and this regardless of the distance between said bar and rail *c*, as when bar *d* is near rail *c* then 55 the nut is adjusted near to the bar, and when the bar, in order that the screen may fill the window, is farther from the rail, then the nut is adjusted farther from the bar. When bar *d* is expanded, as shown, or to any material extent, the space between it and rail *c* affords an ingress for insects, which can enter at the top and find their way indoors, despite lip *e*, and hence it has been the practice to secure to the bar *d* a thin plate of metal, as shown at *j*, Fig. 3, there 60 being a narrow slit therein for the insertion of a small nail, *k*, driven into the main frame, thus allowing the metal plate or guard to slide with bar *d* when the same was moved relatively to the side bar. My improvement in this behalf 65 consists in forming said metal guard with a lip, *l*, bent at right angles to the main part, and so as to inclose the end of lip *e* of bar *d*, and secure the same from injury or splitting from the bar. 70

I claim as my invention—

1. In an adjustable screen, the combination, with the guide-rods *f* and helical springs *h*, mounted thereon, of screw-nuts *i*, threaded on said rods, and adjustable thereon relatively to the adjusting-bar, whereby a uniform force or pressure upon said springs may be maintained, substantially as specified.

2. In an adjustable window-screen, the metallic guard *j*, formed with the angle-lip *l*, to 85 overlie lip *e* of bar *d*, whereby said lip *e* is supported and protected from injury, substantially as specified.

VOLNEY R. CHAMBERLIN.
